J. Lane, Jr.

Constructing Plows.

No 18,750.

Patented Dec. 1, 1857.

UNITED STATES PATENT OFFICE.

JOHN LANE, JR., OF LOCKPORT, ILLINOIS.

IMPROVEMENT IN PLOWS.

Specification forming part of Letters Patent No. 18,750, dated December 1, 1857.

To all whom it may concern:

Be it known that I, JOHN LANE, Jr., of Lockport, in the county of Will and State of Illinois, have invented a new and useful Improvement in the Mode of Constructing Steel Plows; and I do hereby declare that the following is a full, clear, and exact description of the same, reference being had to the accompanying drawings, forming part of this specification, in which—

Figure 1 is a plan or top view of a steel plow constructed after my improved mode. Fig. 2 is a side view of the landside of the same. Fig. 3 is a similar view, showing the landside-bar or foundation drawn out from its proper position. Fig. 4 is an inverted plan of the plowshare as constructed after my improved mode. Fig. 5 is a detached perspective view of the landside-bar and foundation of the plowshare. Figs. 6 and 7 are inverted views of an ordinary plow. Figs. 8, 9, 10, and 11 are diagrams for illustrating the superior utility of my invention over the ordinary mode of constructing plowshares.

Similar letters of reference in each of the several figures indicate corresponding parts.

My invention relates particularly to plowshares which present on all sides a steel surface or exterior to the soil; and the nature of the improvement made by me consists, first, in a rigid foundation or frame constructed with a taper point and an inclined flange which projects nearly at right angles from the landside of the plow underneath the mold-board and lay, for use in combination with a yielding steel mold-board, a yielding steel lay, which has a complete yielding taper socket at its point, and with a steel landside-facing, as presently shown.

By having the foundation or frame formed as stated it serves for perfectly supporting the mold-board and lay and the steel landside-facing and keeping the same in form, and likewise admits of the use of a complete taper socket on the end of the lay, its point serving as a mandrel whereon to bend the sheet-steel in forming the steel point of the lay, by using which form of socket, made and constructed thus, all necessity of welding the lay to a short bar which is bolted to the landside is avoided, and thus expense in manufacturing reduced; and the socket thus formed is a much more effective means than the ordinary lock, as in Jewett's plow, for keeping the point of land-

side-bar in place, it being impossible with the socket for it to change its position, whereas with the lock it not unfrequently springs and shifts its place, the bolts wearing and allowing this. And while these advantages result from the socket, greater advantages result from the construction of the foundation or frame, this construction giving a rigidity to the whole structure when completed, although made of steel; and in case the lay should, while removed and being sharpened, or the mold-board under undue strain at certain points be sprung out of form, the original form of the plowshare will always be retained, as the foundation is unyielding, and therefore all that is necessary under the circumstances just named is to adjust the lay and mold-board to the frame and screw up the bolts until the former conform to the latter, which will always be the case, because the coupling-brace and the flange prevent the landside-bar twisting in the socket of the lay and conforming to the form of the same and the mold-board.

To enable others skilled in the art to make and use my invention, I will proceed to describe its construction and operation.

A represents the landside-bar; E, the taper point; F, the inclined flange projecting nearly at right angles from the upper edge of the landside-bar, underneath the mold-board and lay; B, the mold-board; C, the lay; D, the long taper socket on the lay; G G', the brace and coupling iron, made in one piece; H, the steel landside-facing.

The point E on the landside is made of taper form, with three sides. The point E thus formed is made to serve as a mandrel whereon to form the socket D, which is the full length of the point, which is formed by bending the sheet-steel around the mandrel taper point, as shown in Fig. 4. The steel thus bent around requires no welding, and the socket formed is complete at top, bottom, and on the landside of the plow.

To the flange F the mold-board and lay are screwed, as shown in Figs. 1 and 4. The coupling G serves for uniting the lay and mold-board, while the brace serves for combining them with the foundation or frame, and by thus uniting them by a coupling-iron and brace formed of one piece, as in Fig. 10, instead of in two pieces, as in Fig. 9, there is no chance for the coupling to shift or move independent of

the brace, as in Fig. 9, and therefore the lay and mold-board cannot, even when undue strain is upon them, twist the plow out of shape, as in Figs. 9 and 11; and therefore, although the lay may under certain circumstances spring up, as in Fig. 10, so long as the plow retains its original and proper form the lay and mold-board can again be readily made to conform thereto by driving home the point of the landside-bar and tightening up the screws *f*.

In Fig. 6 may be seen the ordinary method of forming the lock of the lay and landside by welding the lay to a short piece of iron, *c*, which is bolted to the landside-bar; and in Fig. 7, at *d*, may be seen the difficulty to be encountered from this method. This difficulty results from the bolts wearing and becoming loose and allowing the iron and lay to drop or pull down, as shown in Fig. 7, and the plow consequently to run deeper and badly, and causing a bad joint at *e*, which will cause the plow to clog and hold the soil.

The advantages of my improvement are very great, although the changes made are seemingly slight.

There are many places in the west that the plow is obliged to be made all of steel in its working part; and, again, there must be no shoulder or one piece overlapping the other, as is seen in the plow of Ira Reynolds, 1855.

Plows of steel are very liable to be warped and sprung from place and shape in sharpening the lay and in plowing in ground which

is stony or filled with roots; and many devices have been resorted to to keep the lay in its place; but none of them accomplish the object as well as mine, which not only keeps the lay in proper place, but if it is warped or sprung in being sharpened it will be correctly brought in place when secured to the plow by the taper-pointed and flanged landside-bar and combined brace and coupling-iron.

The socket in my method being long and completely incasing the taper end of the landside-bar, it is impossible that the lay shall spring up or down at this point without bending the landside, which is not possible, owing to its rigidity, whereas when the lay is only locked on the landside by a part of a notch or socket, as in the plow of Gill, 1855, and others of like arrangement, these difficulties are not unfrequently experienced.

What I claim as my invention, and desire to secure by Letters Patent, is—

The rigid foundation or frame, when constructed with a taper point and inclined flange which projects nearly at right angles from the landside of the plow underneath the mold-board and lay, for use in combination with a yielding mold-board, a yielding steel lay which has a complete taper socket at its point, and with a steel landside-facing, substantially as and for the purposes set forth.
